CLAIM

The ornamental design for a pipe securing device, as shown and described.

DESCRIPTION

FIG. 1 is a perspective view of a pipe securing device; FIG. 2 is a front view of the pipe securing device; FIG. 3 is a back view of the pipe securing device; FIG. 4 is a side view of the pipe securing device; FIG. 5 is another side view of the pipe securing device; FIG. 6 is a top view of the pipe securing device; and, FIG. 7 is a bottom view of the pipe securing device. The broken line shown in the drawings are for the purpose of illustrating portions of the pipe securing device that form no part of the claimed design.
